US00D955952S

(12) **United States Design Patent** (10) **Patent No.:** **US D955,952 S**
(45) **Date of Patent:** **** Jun. 28, 2022**

(54) **DOOR FOR A UTILITY VEHICLE**

- (71) Applicant: **Polaris Industries Inc.**, Medina, MN (US)
- (72) Inventors: **R. Mark Lopera**, Lake Elsinore, CA (US); **Jeremy M. Brown**, Menifee, CA (US); **Steven D. Wilcox**, Moreno Valley, CA (US)
- (73) Assignee: **Polaris Industries Inc.**, Medina, MN (US)
- (**) Term: **15 Years**
- (21) Appl. No.: **29/699,429**
- (22) Filed: **Jul. 25, 2019**
- (51) **LOC (13) Cl.** **12-16**
- (52) **U.S. Cl.** **D12/196**
- (58) **Field of Classification Search**

(57) **CLAIM**

We claim the ornamental design for a door for a utility vehicle, as shown and described.

DESCRIPTION

FIG. 1 is a left, front perspective view of a door for a utility vehicle embodying our new design in accordance to a first embodiment of the present application;

FIG. 2 is a right, rear perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a left, front perspective view of a door for a utility vehicle embodying our new design in accordance to a second embodiment of the present application;

FIG. 10 is a right, rear perspective view thereof;

FIG. 11 is a left side elevation view thereof;

FIG. 12 is a right side elevation view thereof;

FIG. 13 is a front elevation view thereof;

FIG. 14 is a rear elevation view thereof;

FIG. 15 is a top plan view thereof; and,

FIG. 16 is a bottom plan view thereof.

The portions of the door for the utility vehicle shown in broken lines form no part of the claimed design.

1 Claim, 16 Drawing Sheets
